UNITED STATES PATENT OFFICE.

WILLIAM FRANCIS WEAVER, JR., OF LITTLESTOWN, PENNSYLVANIA.

RAIL-JOINT.

SPECIFICATION forming part of Letters Patent No. 584,085, dated June 8, 1897.

Application filed July 13, 1896. Serial No. 599,003. (No model.)

To all whom it may concern.

Be it known that I, WILLIAM FRANCIS WEAVER, Jr., a citizen of the United States, residing at Littlestown, in the county of Adams and State of Pennsylvania, have invented 5 certain new and useful Improvements in Railroad-Rail Joints; and I do hereby declare the following to be a full, clear, and exact description of the invention, such as will enable 10 others skilled in the art to which it appertains to make and use the same.

My invention, while relating in general to the class of railroad-rails, yet contemplates more particularly the provision of means 15 whereby the several sections of rails comprised in each of the tracks of a roadway are so connected together as to approximate very closely, when under the strain incident to the passage of a railroad-train, the action of 20 a single continuous rail without joint, and therefore at all times in perfect alinement throughout the entire length of the roadway.

To the accomplishment of the end above set forth, the invention consists in so forming 25 the abutting ends of the separate rail-sections that the said sections when in position shall be, by the peculiar formation of said joints, held in one and the same plane, so as to practically form, when the said separate sections 30 are held together by the ordinary fish-plate, a single continuous rail having the properties above set forth, whereby a perfectly smooth surface is presented to the periphery of the truck-wheels.

35 The construction, arrangement, and combination of the parts comprised in the invention are hereinafter set forth, and illustrated in the accompanying drawings, wherein—

Figure 1 is a top plan view of two adjoining 40 rail-sections connected together by a joint formed in accordance with my invention. Fig. 2 is a similar top plan view of the parts shown in Fig. 1, the rails separated to clearly show the abutting joint. Fig. 3 is a side elevation of the parts shown in Fig. 1, the fish-plates being removed to more clearly show 45 the joint. Fig. 4. is an end elevation of one of the rail-sections. Fig. 5 is a side elevation of one of the sections of rail shown in Fig. 2. Fig. 6 is a top plan view of two adjoining 50 rail-sections, showing a modified form of the joint therebetween, the rails being in contact.

Fig. 7 is a similar top plan view of the rail-sections shown in Fig. 6, the same being separated to more clearly show the joint. 55

Referring to the drawings, wherein similar letters of reference denote similar parts, A and B designate sections of ordinary railroad-rails, and C the abutting joint of said rails, which latter, it will be observed, is not cut at right angles to the axis of the rails, as is the usual practice in this art, but rather is preferably cut at acute angles to said axis—that is to say, the said joint extends from side to side of the rails at the head and base thereof— 65 whereby I am enabled to attain ends not otherwise attainable—as, for instance, to provide the said joints at each side of the rail with interlocking portions, whereby the rails are maintained at all times in perfect alinement and so present a smooth unbroken surface to the truck-wheels. 70

As above stated, I provide the joint C at opposite sides of the rails with interlocking portions, which I form as follows, viz: *d e* 75 designate short vertical joint-faces which are formed in the side flanges of both the head and base at a short distance from the edges thereof and parallel with the axis of the rails. *f* and *g* designate short vertical joint-faces 80 which extend outwardly from one end of each of the faces *d* and *e* and at acute angles with said latter faces to the side edges of the rails, as shown. I connect the remaining ends of the faces *d* and *e* by vertical faces *h*, which 85 latter extend diagonally across the body of the rails A B from one to the other of the faces *d* and *e*.

I preferably make the joint-faces of both the head and base of the rails practically the 90 same in length, and because of this fact, in connection with the fact that said head and base vary greatly in width, the joint C in the head and base of the rails will extend transversely of said rails at different angles, as 95 shown.

I preferably abut the web H of the rails A and B squarely together at a point intermediate of the ends of the joint C and thereby form shoulders K, which extend below the 100 head flanges of the opposing rails and aid very materially to strengthen and support the joint, as will be readily understood.

I provide the ends of the rails A and B with

suitable apertures *l* to receive bolts *M*, that secure the fish-plates *N* in position to said rails. (See dotted lines in Fig. 4.)

In practice the rails are placed together, as shown in Fig. 1, the different faces *h* and *h*, *d* and *e*, and *f* and *g*, comprised in the joint *C*, engaging, as shown, and the shoulders *k* of each rail-section *A* and *B* extending below and thus supporting the head of the remaining rail-section. The fish-plate *N* is now secured in place over the joint by the bolts *m* in the ordinary manner. When thus secured together, the separate rail-sections cannot be displaced by the strains incident to the passage of a train; the interlocking portions bounded by the faces *d* and *e* and *f* and *g* operating most effectually to this end.

In the modified form of joint shown in Figs. 6 and 7 the joint *C* is in outline somewhat different, but in action is similar to the joint shown in Figs. 1 and 2.

I claim and desire to secure by Letters Patent—

1. In a railroad-rail, an interlocking joint, comprising vertical faces *d*, and *e*, at opposite sides of and parallel with the axis of the rail, vertical faces *f*, and *g*, projecting outwardly from said faces *d*, and *e*, at acute angles therewith and vertical faces *h*, extending diagonally across the rail between said faces *d*, and *e*, substantially as described.

2. In an interlocking rail-joint, vertical faces *d*, and *e*, connected to, and by vertical faces *f*, *g*, and *h*, at angles to said faces *d*, and *e*, shoulders *k*, on the web of the rail and fish-plates *N*, substantially as described.

In testimony whereof I have affixed my signature in presence of two witnesses.

WILLIAM FRANCIS WEAVER, JR.
